DESIGN FOR A BOTTLE

Salvator D'Addario, New York, N. Y., assignor to
Krueger Beverage Company, Newark, N. J., a
corporation of New Jersey

Application October 12, 1937, Serial No. 72,134

Term of patent 14 years

To all whom it may concern:

Be it known that I, Salvator D'Addario, a citizen of the United States and a resident of New York, in the county of New York and State of New York, have invented a new, original, and ornamental Design for a Bottle, of which the following is a specification, reference being had to the accompanying drawing, forming part thereof.

The figure is a front elevation of a bottle showing my new design.

The essential feature of my design resides in the spirally arranged ribs on the upper portion of the bottle in combination with the helically curved lines on the lower label portion.

I claim:

The ornamental design for a bottle as shown and described.

SALVATOR D'ADDARIO.
